UNITED STATES PATENT OFFICE.

IVAN GOSAR, OF BETHLEHEM, PENNSYLVANIA.

BULB-REPLACING TOOL.

1,368,717.

Specification of Letters Patent. Patented Feb. 15, 1921.

Application filed August 28, 1919. Serial No. 320,429.

To all whom it may concern:

Be it known that I, IVAN GOSAR, a citizen of the United States, residing at Bethlehem, in the county of Northampton and State of Pennsylvania, have invented certain new and useful Improvements in Bulb-Replacing Tools, of which the following is a specification.

This invention relates to a tool or device particularly designed for replacing blown out or worn out electric incandescent bulbs, in ceiling fixtures, signs or in other places where they are out of the normal reach of the person replacing them, and an object of the invention is to provide a device of this nature by means of which the worn out or broken bulb may be easily and quickly removed from the fixture and replaced with a good bulb without necessitating the use of a ladder or the like to permit the person removing and replacing the bulb to reach it.

Another object of this invention is to provide in a bulb-replacing tool, a plurality of resilient bulb-gripping members or fingers, which are carried by a rotatable sleeve, the said sleeve being in turn supported upon a suitable standard, or stem, and to provide means for contracting the bulb gripping fingers to cause them to securely and firmly grip a bulb, to hold it when it is either unscrewed from or screwed into its socket, and further to provide means whereby the bulb gripper may be moved about, upon a pivot point as an axis through an arc of substantially 145° to permit it to engage bulbs which are supported at various angles.

A further object of this invention is to provide means for contracting the bulb-grip structure about a bulb which means includes a nut adapted to be threaded upon the gripping fingers or arms to contract them, which nut normally rotates with the gripping structure, during the screwing of a bulb into or unscrewing of it from the socket, and to provide means including sharpened arms for engagement with lugs carried by the nut to hold the lug against rotation to permit it to be threaded upwardly upon or downwardly from the gripping fingers or arms, during the rotation of the gripper structure, and also to provide means for moving the lug engaging nut into and out of engagement with the lug, which means include a rack bar operable by a rotary pinion which is rotated from the hand

grip end of the handle or supporting stem of the tool.

Other objects of the invention will appear in the following detailed description taken in connection with the accompanying drawing, forming a part of this specification and in which drawing:

Figure 1 is a side elevation partly in section of the improved bulb replacing tool illustrating, in dotted lines, different positions of the bulb gripper structure.

Fig. 2 is a fragmentary side elevation of the bulb replacing tool taken at right angles to Fig. 1.

Fig. 3 is a detail section of a part of the tool illustrating the manner of mounting the bulb gripper.

Fig. 4 is a detail perspective view of a pawl carried in the tool structure for permitting rotation of the bulb gripper upon the supporting stem, and to prevent longitudinal movement of the bulb gripper structure upon a supporting stem.

Fig. 5 is a cross section taken on the line 5-5 of Fig. 1, and

Fig. 6 is a cross section taken on the line 6-6 of Fig. 3.

Referring more particularly to the drawings, wherein like characters indicate like and corresponding parts throughout the several views, the bulb replacing tool includes a supporting stem structure 10, comprising a sleeve 11, which has its upper end secured in any suitable manner as by means of a flanged collar 12 to the supporting frame work 13 of the operating gear sets of the tool.

This frame work 13 has a shaft 14 journaled therein upon which shaft a gear 15 is mounted for rotation upon the shaft. The gear 15 has a stem 16 formed integrally therewith and extending radially from the periphery of the gear, the teeth 17 of the gear being interrupted by a portion of the periphery of the gear to permit the juncture of the stem 16 with the gear.

The normal position of the stem 16 is vertical and it has a sleeve 18 rotatably mounted thereon. The sleeve 18 is provided with diametrically opposed openings 19 extending therethrough which communicate with an annular channel 20 formed in the stem 16. Pawls 22 are pivotally carried by the stem 16, and these pawls 22 have forked ends 23 which engage about portions of the

stem 16 and are pivoted thereto and also are provided with substantially flat inserting portions 24 which are inserted through the openings 19 and engaging in the annular channel 20 for connecting the sleeve 18 to the stem 16 so as to permit rotary movement of the sleeve relative to the stem, and prevent relative longitudinal movement of the stem and sleeve. A pair of these pawls 22 5 are provided, and they are connected by a contractile spiral spring 25, connected to extensions 26 formed upon the pawl structures 22 for normally urging the portions 24 thereof toward each other and consequently into the channel 20 to prevent the accidental disconnection of the ends 24 from the openings 19.

The sleeve 18 has a plurality of resilient fingers 28 formed upon its upper end, and these fingers 28 are concavo-convexly curved longitudinally as clearly shown in Figs. 1 and 2 of the drawings, for fitting about electric incandescent lamp bulbs. Layers of felt or analogous material as indicated 20 at 29 are preferably attached to the inner surfaces of the arms or fingers 28 so as to frictionally grip an electric bulb, to permit the bulb to be engaged by the fingers 28 with sufficient friction or strength to cause the 25 bulb to be rotated synchronously with rotation of the fingers and sleeve 18 about the stem 16 as its support. The resilient fingers or arms 28 are normally relieved from tension so that they may be easily slipped over 30 an electric lamp bulb, and they have portions of their outer surfaces near their lower ends screw threaded as shown at 30, the said threads engaging with the internal thread 31 of a nut structure 32. This nut 35 32 has a pair of diametrically opposed outwardly extending lugs 33, formed upon the periphery thereof. When it is desired to move the nut 32 upwardly or downwardly along the threaded portion 30 of the fingers 28, it is necessary to hold the nut stationary 40 with respect to the fingers 28, and for this purpose, stop arms 34 are provided, one for engagement with each of the lugs 33. The arms 34 are connected to a bar 35, which 45 rises from the frame 13, and is substantially parallel to the sleeve 18 for a portion of its length, the said rod being provided with an angled portion 36 to connect it to a rack bar 37. The rack bar 37 extends through a 50 suitable guide 38 which is pivotally mounted upon the shaft 14 and the teeth of the rack 37 mesh with a pinion 39 which is mounted upon the shaft 14 and meshes with the peripheral teeth 40 of a gear 41. The gear 41 55 is supported by a shaft 42 which is in turn supported from the shaft 14 by a suitable supporting bracket 43. The gear 41 is provided with teeth 44 on the face thereof, and these teeth 44 mesh with a gear 45, carried 60 by the upper end of a sleeve 46. The sleeve

46 is mounted within the housing sleeve 11, and projects below the lower end thereof having a hand grip 47 mounted upon its lower end to permit manual rotation of the sleeve for rotating the gear 45 and consequently rotating the gear 41 and pinion 39 to raise and lower the rack 37 for moving the arms 34 into and out of engagement with the lugs 33.

A second sleeve 48 is mounted within the 70 sleeve 46 and it projects a short distance above the upper end of the sleeve 46 having a gear 49 mounted thereon, which meshes with a gear 50. The gear 50 is carried by a vertical shaft 51, which is supported by 80 suitable brackets 52 and has a beveled gear 53 upon its upper end. The beveled gear 53 meshes with the beveled gear 54 rotatably mounted upon the shaft 14 which in turn meshes with a beveled gear or pinion 55 carried by the lower end of a vertical shaft 56. The shaft 56 rises above the frame 13, and has a gear 57 mounted upon its upper end which meshes with a gear 58. This gear 58 is mounted upon the sleeve 18 being keyed 90 thereto for rotating the sleeve and consequently the gripper head of the tool. The upper end of the shaft 56 is supported by a suitable supporting bracket 59 carried by the sleeve 18 which also acts as means for 95 limiting the downward movement of the nut 32. A beveled pinion 60 is mounted upon the lower end of the sleeve 48 below the hand grip 47 and a beveled gear 61 meshes therewith. The gear 61 is carried 100 by a shaft or pin 62, which has a hand crank or handle 63 thereon, for manually rotating the shaft and consequently the gear 61. The shaft 62 is supported by a suitable supporting hanger structure 64, which is 105 attached to the housing sleeve 11 in any suitable manner such as by a collar 65. When the beveled gear 61 is rotated by means of the hand crank 63, the rotation thereof will be imparted to the sleeve 48 and 110 from this sleeve through the gears 49 and 50 to the shaft 51 which in turn transmits the motion through the beveled gears 53, 54 and 55 to the shaft 56 and from this shaft to the gears 57 and 58 to the gear 18 and 115 consequently to the gripper head structure which includes the resilient fingers 28.

These beveled gears 53, 54 and 55, are provided to permit the rotation of the sleeve 18 and gripper head structure at various 120 angular adjustments of the gripper head as indicated in dotted lines in Fig. 1 of the drawings, and this adjustment of the gripper head is permitted by rotation of the gear 15. This gear 15 meshes with a pinion 125 66, which is mounted upon a suitable supporting shaft 67. The shaft 67 is supported by the bracket 43 and by a second supporting bracket 68, and it carries a beveled gear 69 thereon, which meshes with a 130

beveled pinion 70. The pinion 70 is carried by the upper end of a stem 71, which extends downwardly through the sleeve 46, and projects below the lower end of the sleeve 48. A hand grip 72 is mounted upon the lower end of the stem or rod 71, for facilitating the manual rotation thereof to vary the angle of the sleeve 18, stem 16, and of the bulb gripping head or gripper carried by the sleeve 18 in accordance with the angle at which the bulb to be replaced is supported.

In use, the stem 71 is first rotated, to position the gripper head at the proper angle to permit its insertion over the bulb to be replaced, after which the tool is moved to slip the arms 28 over the bulb to be removed, and the sleeve 46 is rotated for raising the rod 37 and consequently moving the stop arms 34 into engagement with the lug 33 for arresting or preventing rotation of the nut 32. The crank handle 63 is then rotated and the nut 32 is threaded upwardly upon the threaded portion 30 of the resilient fingers 28 forcing these fingers inwardly and causing the grip 29 to frictionally grip the bulb. The upward movement of the nut 32 is then arrested by rotation of the sleeve 46 in the direction opposite to that in which it was originally rotated for bringing the rack 37 downwardly to permit the nut to rotate with the gripper head or the fingers 28 and sleeve 18 and rotation of the sleeve 48 is again taken up, for rotating the arms 28 about the stem 16 until the bulb is unscrewed from its socket after which the tool is lowered and the nut 32 is moved downwardly on the threaded portions of the arms to permit the arms to spread, for releasing the bulb by again operating the sleeve 45 to move the arm 34 into engagement with the lug 33 and rotating the sleeve 18 in a direction oppositely to that in which it was rotated for tightening the nut upon the arm, and after the worn or broken bulb has been released a good bulb may be replaced therein, and the arms or resilient fingers 28 tightened thereon and the tool raised through the medium of the column including the housing sleeve 11, sleeves 46, 48 and stem 71, so that the bulb is screwed into the socket by the rotation of the sleeve 48 through the medium of the crank handle 63 and the gears 60 and 61.

Changes in details may be made without departing from the spirit of this invention; but,

I claim:

1. In a bulb replacing tool, the combination of a supporting structure, a bulb gripping structure, means for rotating said gripping structure about an axis longitudinally of the tool, means for rotating said bulb gripping structure about an axis transversely of the length of the tool to vary the

angle at which the gripping structure extends with respect to the supporting structure, a nut engaging said bulb gripping structure, and means whereby said nut is fed upwardly upon said bulb gripping structure to securely grip a bulb.

2. In a bulb replacing tool, the combination with a supporting structure, a gear rotatably carried thereby, a stem carried by said gear and extending radially from the periphery thereof, a sleeve rotatably mounted upon said stem, and a plurality of resilient bulb gripping fingers carried by the outer end of said sleeve.

3. In a bulb replacing tool, the combination of a supporting structure, a gear rotatably carried thereby, a stem carried by the gear and extending radially from the periphery thereof, a sleeve rotatably mounted upon said stem, a plurality of resilient bulb gripping fingers carried by the outer end of said sleeve, and means for moving said fingers into and out of gripping engagement with a lamp bulb.

4. In a bulb replacing tool, the combination of a supporting structure, a gear rotatably carried thereby, a stem carried by the gear and extending radially from the periphery thereof, a sleeve rotatably mounted upon said stem, a plurality of resilient bulb gripping fingers carried by the outer end of said sleeve, and means carried by said stem and engaging said sleeve to prevent relative longitudinal movement of the sleeve and stem.

5. In a bulb replacing tool, the combination of a supporting structure, a gear rotatably carried thereby, a stem carried by the gear and extending radially from the periphery thereof, a sleeve rotatably mounted upon said stem, a plurality of resilient bulb gripping fingers carried by the outer end of said sleeve, means carried by said stem and engaging said sleeve to prevent relative longitudinal movement of the sleeve and stem, and means for moving said fingers into and out of gripping engagement with the lamp bulb.

6. In a bulb replacing tool, the combination of a supporting structure, a gear rotatably carried thereby, a stem carried by said gear and extending radially from the periphery thereof, a sleeve rotatably mounted upon said stem, a plurality of resilient bulb gripping fingers carried by the outer end of said sleeve, said bulb gripping fingers having screw threads upon a portion of their outer surface, a nut adapted to be threaded upwardly about said fingers to move them into a bulb gripping position or downwardly of the fingers to permit movement of the fingers out of a bulb gripping position.

7. In a bulb replacing tool, the combination of a supporting structure, a gear rotatably carried thereby, a stem carried by

said gear and extending radially from the periphery thereof, a sleeve rotatably mounted upon said stem, a plurality of resilient bulb gripping fingers carried by the outer end of said sleeve, said bulb gripping fingers having screw threads upon a portion of their outer surface, a nut adapted to be threaded upwardly about said fingers to move them into a bulb gripping position or 10 downwardly of the fingers to permit movement of the fingers out of a bulb gripping position, lugs carried by said nut, and means adapted for engagement with said lugs to hold the nuts stationary during rotation of the gripping means, and means for rotating said gripping fingers about an axis longitudinally of the tool.

8. In a bulb replacing tool, the combination of a supporting structure, a gear rotatably carried thereby, a stem carried by said gear and extending radially from the periphery thereof, a sleeve rotatably mounted upon said stem, a plurality of resilient bulb gripping fingers carried by the outer end of said sleeve, said bulb gripping fingers having screw threads upon a portion of their outer surface, a nut adapted to be threaded upwardly about said fingers to move them into a bulb gripping position or downwardly 20 of the fingers to permit movement of the fingers out of a bulb gripping position, lugs carried by said nut, means adapted for engagement with said lugs to hold the nuts stationary during rotation of the gripping means, means for rotating said gripping fingers about an axis longitudinally of the tool, and means for moving said lug engaging means out of engagement with the lugs to permit rotation of the nut with said resilient fingers.

9. In a bulb replacing tool, the combination of a supporting structure, a gear rotatably carried thereby, a stem carried by the gear and extending radially from the periphery thereof, a sleeve rotatably mounted upon the stem, a plurality of resilient bulb gripping fingers carried by the outer end of the sleeve, means for rotating said sleeve upon said stem, and means carried by the stem and engaging said sleeve to prevent relative longitudinal movement of the sleeve and stem, said fingers having screw threads upon a portion of their outer surfaces near the upper sleeve, a nut, means for holding said nut stationary during rotation of the said bulb gripping fingers to permit the nut to be threaded upwardly upon or downwardly of the threaded portions of the fingers to move the fingers into or out of bulb gripping position.

10. In a bulb replacing tool, the combination of a supporting structure, a gear rotatably carried by the supporting structure, a stem carried by said gear and extending radially from the periphery thereof, a sleeve

rotatably mounted upon said stem, and means for rotating said sleeve upon said stem and about an axis longitudinally of the tool, means for rotating said gear to move said sleeve and stem about an axis transversely of the length of the tool, and means carried by the stem and engaging the sleeve to prevent relative longitudinal movement of the sleeve and stem.

11. In a bulb replacing tool, the combination of a supporting structure, a gear rotatably carried by the supporting structure, a stem carried by the gear and extending radially from the periphery thereof, a sleeve rotatably mounted upon said stem, a plurality of resilient bulb gripping fingers carried by the outer end of the sleeve, and means operatively connected to said sleeve for rotating the sleeve and bulb gripping fingers upon an axis longitudinally of the supporting structure, said fingers having screw threads upon a portion of their outer surfaces adjacent said stem, a nut, radial lugs extending from said nut, arms for engagement with said lugs to hold the nut against rotation to permit it to be threaded upwardly upon or downwardly of said fingers upon rotation of the fingers for moving the fingers into or out of bulb gripping position, a rack bar, means for moving said rack longitudinally, said rack connected to said lug engaging arms for moving the arms into and out of engagement with the nut carried lug.

12. In a bulb replacing tool, the combination of a supporting structure, a sleeve carried by the supporting structure and rotated about an axis longitudinally thereof, a plurality of resilient bulb gripping fingers carried by the outer end of said sleeve, means for rotating the sleeve, said fingers provided with screw threads upon a portion of their outer surfaces, a nut adapted to be threaded upon or on a threaded portion of said fingers for moving the fingers into and out of bulb gripping position.

13. In a bulb replacing tool, the combination of a supporting structure, a sleeve carried by the supporting structure and rotated about an axis longitudinally thereof, a plurality of resilient bulb gripping fingers carried by the outer end of said sleeve, means for rotating the sleeve, said fingers provided with screw threads upon a portion of their outer surfaces, a nut adapted to be threaded upon or on a threaded portion of said fingers for moving the fingers into and out of bulb gripping position, a rack bar carried by said supporting structure, means for moving said rack bar longitudinally, stop arms carried by said rack bar and adapted to engage said nut to hold the nut against rotation during rotation of said resilient fingers to permit the threading of the nut upon or off the fingers, said rack bar adapted to be moved to move said nut engaging arms for

engagement with the nut to permit the nut to rotate with the rotation of the fingers.

14. In a bulb replacing tool, the combination of a supporting structure, a sleeve carried by the supporting structure and rotated about an axis longitudinally thereof, a plurality of resilient bulb gripping fingers carried by the outer end of said sleeve, means for rotating the sleeve, said fingers provided with screw threads upon a portion of their outer surfaces, a nut adapted to be threaded upon or off a threaded portion of said fingers for moving the fingers into and out of bulb gripping position, a rack bar carried by

said supporting structure, means for moving 15 said rack bar longitudinally, stop arms carried by said rack bar and adapted to engage said nut to hold the nut against rotation during rotation of said resilient fingers to permit the threading of the nut upon or off the 20 fingers, said rack bar adapted to be moved to move said nut engaging arms for engagement with the nut to permit the nut to rotate with the rotation of the fingers, and means connected to said sleeve for rotating the 25 sleeve and fingers about an axis transversely of the length of the tool.

IVAN GOSAR.
